UNITED STATES PATENT OFFICE.

EDWARD ANCHEL, OF NEW YORK, N. Y., ASSIGNOR OF ONE-HALF TO JONAS HECHT, OF NEW YORK, N. Y.

DESIGN FOR BRAID.

No. 38,239.

Specification for Design.

Patented Sept. 18, 1906.

Application filed July 28, 1906. Serial No. 328,274. Term of patent 7 years.

To all whom it may concern.

Be it known that I, EDWARD ANCHEL, a subject of the Czar of Russia, residing in New York, in the borough of Manhattan, county and State of New York, have invented a new, original, and ornamental Design for Braids, of which the following is a specification, reference being had to the accompanying drawing, forming part thereof.

The figure is a plan view of the braid, showing my new design.

I claim—

The ornamental design for braid, as herein shown.

EDWARD ANCHEL.
